ADJUSTING SCREW FOR FIREARMS

Charles H. Cleveland, Springfield, Mass., assignor
to the United States of America as represented
by the Secretary of War

Application March 8, 1950, Serial No. 148,441

3 Claims. (Cl. 89—198)

(Granted under the act of March 3, 1883, as
amended April 30, 1928; 370 O. G. 757)

1

The invention described herein may be manufactured and used by or for the Government for governmental purposes without the payment of any royalty thereon.

This invention relates to means for varying the tension of a firearm buffer spring and is more particularly directed to an improved adjusting screw therefor.

Automatic firearms are commonly provided with some means for cushioning the shock of a recoiling bolt immediately prior to the counter-recoil movement thereof. For example, the caliber .50 Browning machine gun utilizes a set of washer-like springs seated in a tubular housing which extends rearwardly from the back plate. These springs are arranged to be initially compressed between a buffer member mounted in the front end and an adjusting screw threaded into the rear end of the tubular housing. Thus, adjustment of the screw serves to control the extent of the buffer action provided on the recoiling bolt in the gun.

When the adjusting screw is assembled into the tubular spring housing to the depth desired, the reduced diameter end of a spring biased plunger projects from the side of the screw into either one of a pair of oppositely disposed slots provided in the walls of the housing and thereby serves to lock the screw to the housing. Consequently, it is necessary to depress the plunger by means of a suitable tool or drift inserted through one of the slots before the screw can be rotated for further adjustment or disassembly purposes. When 180° rotation thereof has been made, the reduced end of the plunger will automatically project into the other of the housing slots. It can thus be readily seen that the aforesaid manipulation of the plunger depressing tool must be repeated at every 180° turn of the adjusting screw. Obviously such procedure is tedious and time consuming.

It is therefore an object of this invention to provide improved means for locking and unlocking the adjusting member of a firearm buffer mechanism.

It is a particular object of the present invention to provide a self-locking and unlocking adjusting screw for the buffer assembly of a caliber .50 Browning machine gun.

The specific nature of the invention as well as other objects and advantages thereof will clearly appear from a description of a preferred embodiment as shown in the accompanying drawings, in which:

2

Fig. 1 is a perspective view of the adjusting screw;

Fig. 2 is a perspective view showing the adjusting screw assembled to the buffer housing of a caliber .50 Browning machine gun.

Fig. 3 is a cross-sectional view taken along the line 3—3 in Fig. 2;

Fig. 4 is a detail perspective view of the locking plunger of this invention;

Fig. 5 is a perspective view of the latch arranged to actuate the plunger between its locking and unlocking positions;

Fig. 6 is a fragmentary cross-sectional view showing the latch in its depressed position; and

Fig. 7 is a cross-sectional view taken along the line 7—7 in Fig. 6.

Referring now to the drawing there is illustrated in Figs. 2 and 3 a back plate member particularly designed for use with Browning type machine guns. Such back plate essentially comprises a substantially rectangular portion 5 arranged to serve as the rear end wall of the receiver (not shown) and an integral rearwardly extending tubular housing 6. A buffer spring 7 consisting of a set of slightly concave washer-like members 8 is so disposed within housing 6 that the concave and convex faces thereof alternate in succession. Spring 7 seats against a cylindrical buffer member 9 slidably but snugly disposed in a centrally located counterbored opening 10 extending through rectangular portion 5. Member 9 is provided with an annular beveled surface 11 arranged to mate with a similarly beveled shoulder 12 formed in opening 10 so that the front end of member 9 protrudes slightly beyond the back plate rectangular portion 5 for contact with a recoiling bolt (not shown). The inner periphery of the rear end portion of housing 6 is threaded as shown at 13 for receiving a disk-like adjusting screw 14.

A longitudinal axial hole 16 is provided through screw 14 and a cylindrical recess 15 is formed in the rear face thereof on either side of hole 16. Recesses 15 are in alignment with the vertical axis of hole 16. A transverse counterbored hole 17 forms a shoulder 18 and also extends through screw 14 so as to intersect axial hole 16 substantially at right angles.

A plunger 19 is slidably mounted in counterbored hole 17 and is arranged to be biased by a coil spring 20 interposed between shoulder 18 and one end of plunger 19. The other end thereof is of reduced diameter as best shown at 21 in Fig. 4 and is normally arranged to extend into either of a pair of longitudinal slots 22 diametri-

cally disposed on opposite sides of housing 6. A section of plunger 19 is cut away as illustrated at 23 and one side wall of such cut-out section is provided with a ramp surface 24.

A latch 25 is slidably disposed in axial hole 16 of adjusting screw 14 so as to extend through and beyond plunger cut-out section 23. Such latch comprises a cylindrical head 26 and an integral body 27 slabbed off as shown at 28. Body 27 terminates in a hook portion 29 and is also provided with a cam surface 30 extending upwardly therefrom.

When properly assembled, the indented portion of body 27 between hook 29 and cam surface 30 receives plunger ramp surface 24 under the bias of spring 20. In this position, the reduced end 21 of plunger 19 extends into one of housing slots 22 thereby preventing any further rotation of adjusting screw 14 which has been threaded into housing 6 to the extent determined by the amount of tension desired in buffer spring 7.

However, when latch 25 is depressed by means of a suitable tool 31 such as disclosed in Fig. 6, plunger 19 is cammed to the position shown in Fig. 7 by contact of latch cam surface 30 on ramp surface 24. Consequently plunger end 21 is withdrawn out of slot 22 allowing rotation of screw 14. Tool 31 is, of course, provided with a central pin 32 arranged to depress latch 25 when a pair of oppositely disposed studs 33 are fully seated in recesses 15. Thus when tool 31 is rotated, adjusting screw 14 will be rotated in the same direction to advance or retract in housing 6. Upon removal of tool 31, spring 20 will bias plunger ramp surface 24 against latch cam surface 30 thereby returning latch 25 to a pre-depressed position. If either one of slots 22 is aligned with counterbored hole 17 in screw 14, plunger 19 will assume the locked position shown in Fig. 3. However, if such alignment is not present when rotation of screw 14 is halted, the vibration caused by firing of the gun will automatically rotate screw 14 until the aforesaid alignment is attained.

Thus there is here provided simple yet positive means for locking and unlocking the adjusting screw in the buffer mechanism for a Browning machine gun. The structure here disclosed entirely eliminates the prior art necessity for halting the rotation of the adjusting screw after each 180° turn in order to move the tool to the new position reached by the plunger. It is obvious that the latch of this invention will hold the plunger end out of the slots in the buffer housing as long as it is depressed by means of the tool. Furthermore, the tool itself is one of the standard units supplied with the gun and can be readily converted to the use here required by merely adding the centrally located pin. Such addition will not interfere with the other uses to which the tool is to be put.

I claim:

1. In a buffer mechanism for a firearm back plate having a rearwardly extending tubular buffer housing, the combination of, a buffer member longitudinally mounted in the back plate so as to protrude slightly therefrom, an adjust-

ing screw threadably secured into the rear end of the buffer housing, a buffer spring interposed between said buffer member and said adjusting screw whereby rotative movement of the latter varies the amount of resistance of the former to impact, the housing having a pair of longitudinally extending slots formed on opposite sides thereof, a spring biased plunger transversely mounted in said adjusting screw and normally arranged to protrude therefrom into one of said slots in said housing for preventing rotative movement of said screw, a latch slidably carried in said screw for limiting the slot-engaging movement of said plunger, and cam means on said latch for actuating said plunger out of said housing slots when said latch is depressed into said adjusting screw.

2. Means for unlocking a buffer adjusting screw in a firearm buffer housing, comprising, a plunger transversely disposed in the adjusting screw; spring means normally urging one end of said plunger into engagement with the buffer housing to prevent rotation of the adjusting screw, said plunger having a substantially rectangular cut-out section and a ramp portion on one side wall thereof, a latch longitudinally disposed in the adjusting screw for slidable movement, said latch comprising a cylindrical head and a slabbed body terminating in a hook portion, said plunger ramp portion arranged to be engaged by said latch hook portion for preventing movement of said latch out of the adjusting screw, and a cam surface on said latch body extending upwardly from said hook portion and arranged to contact the face of said ramp portion in said plunger whereby movement of said latch downwardly into the adjusting screw cams said plunger out of engagement with the buffer housing.

3. In a firearm having a back plate and a buffer housing integral therewith, the combination of, a buffer member slidably protruding through the back plate, an adjusting screw threadably secured in the buffer housing, resilient means interposed between said buffer member and said adjusting screw and arranged to resist rearward movement of said buffer member, a spring-biased plunger transversely mounted in said adjusting screw and normally engaged in the housing thereby preventing rotation of said adjusting screw, said plunger having a ramp portion on one side thereof, a latch longitudinally mounted in said adjusting screw for slidable movement therein, and cam means on said latch cooperating with said ramp portion for retracting said plunger out of the housing thereby permitting rotation of said adjusting screw.
